UNITED STATES PATENT OFFICE.

PAUL KIRGEIS, OF BRESLAU, GERMANY.

MEANS FOR CLOSING STEAM OR OTHER PRESSURE CHAMBERS.

SPECIFICATION forming part of Letters Patent No. 720,155, dated February 10, 1903.

Application filed May 15, 1902. Serial No. 107,461. (No model.)

To all whom it may concern:

Be it known that I, PAUL KIRGEIS, a subject of the German Emperor, residing and having my post-office address at Mathiasstrasse 170, 5 Breslau, in the Empire of Germany, have invented certain new and useful Improvements in Means for Closing Steam or other Pressure Chambers, of which the following is a specification.

10 This invention relates to improvements in means for closing steam and other pressure chambers.

For closing the ends of steam and other pressure chambers cover-plates have hitherto been used, which were fixed externally to 15 flanges on the chambers by means of bolts or studs. One disadvantage of this method is that the screwing of the bolts occupies a considerable amount of time. The bolts also require to be frequently replaced, as they 20 rapidly wear out. Further, it is difficult to render the covers perfectly steam-tight by the means described, for the reason that the steam presses the cover outward, so that the latter 25 is lifted away from the packing in places, even when screwed down very carefully.

The object of the present invention is to close steam-chambers in such a manner that, as with manhole-covers, the covers of the 30 chambers are pressed by the steam inside against flanges, so that the greater the steam-pressure becomes the more tightly the covers fit. To effect this, a slot is provided in the 35 wall of the chamber, through which slot a slide is inserted. The latter is so constructed that when pressed against its seat it closes the slot.

In the annexed drawings, Figure 1 is a vertical section of a steam-chamber with the slide inserted; Fig. 2 an end view, and Fig. 3 a side 40 view.

The steam-chamber is closed by means of the slide *a*, passing through a slot *g* in the chamber, and the lower part of which fits against the inner wall of the chamber and is 45 provided with a rib *b*, which enters a recess formed by the wall of the chamber and a ring *c* of rectangular cross-section. This recess is filled with packing material. One side of the upper external portion of the slide is provided 50 with a rib *d*, fitting the shape of the steam-chamber. The other side has a semicircular projection *e*, which also fits the shape of the

steam-chamber. The rib *d* and projection *e* enter recesses in a collar *f*, riveted or otherwise attached to that part of the chamber in which 55 the slot *g* is provided. A slot in the said collar coincides with the slot *g* in order to afford passage for the slide, and the recesses referred to contain packing. The width of the slots in the collar and chamber is just sufficient to 60 allow the slide and its ribs *b* and *d* to pass through freely. The projection *e* is so shaped that when the slide passes through the slots the said projection extends over and behind the collar *f*. When the slide has been inserted 65 and is pulled forward by some known device, it closes the end of the chamber tightly as soon as the rib *b* enters the packing material provided for it, and at the same time the slot *g* is closed, since the forward movement of the 70 slide causes the rib *d* and the projection *e* to enter the packing material which is provided for them in their respective recesses. The steam-pressure forces the cover so tightly 75 against its seat that leakage of steam is impossible, since every increase of pressure increases the tightness of the cover.

I declare that what I claim is—

1. The combination with a pressure-chamber of a slide passing through a slot in the 80 wall thereof, and adapted to close the open end of said chamber, said slide also closing said slot by means of a rib on one side and a projection on the other side, both adapted to enter recesses in a collar attached to the outside of the chamber, and packing material in 85 said recesses, substantially as described.

2. The combination with a pressure-chamber of a slide passing through a slot in the wall thereof, a rib on said slide adapted to 90 enter a recess formed inside the chamber, a rib and a projection on opposite sides of the external part of said slide both adapted to enter recesses in a collar attached to the outside of the chamber for the purpose of closing 95 the slot on the slide being seated and packing material in the several recesses, substantially as described.

3. The combination with a pressure-chamber of a slide passing through a slot in the 100 wall thereof, a rib on said slide, a ring forming with the inner wall of the chamber a recess into which said rib engages, a semicircular rib on one side of the external part of

said slide, and a semicircular projection on the other side of the external part of said slide, both adapted to enter recesses in a slotted collar attached to the outside of the chamber, for the purpose of closing the slot when the slide is seated and packing material in the several recesses substantially as described.

In witness whereof I have signed this specification in the presence of two witnesses.

PAUL KIRGEIS.
